MANUFACTURE OF WINDOW BAGS

Daniel Belcher, Minneapolis, Minn., and Russell J. Williams, Richmond Heights, and Milton J. Heimos, Lemay, Mo., assignors to Bemis Bro. Bag Company, St. Louis, Mo., a corporation of Missouri

Application July 7, 1949, Serial No. 103,510

7 Claims. (Cl. 154—36)

1

This invention relates generally to the manufacture of window bags and more particularly to the manufacture of window bags of the type having a window of flexible transparent sheet material such as cellophane.

The principal object of the invention is the provision of an apparatus for the continuous and automatic production of window bags of the above-mentioned type wherein the window comprises a relatively small patch of the window-forming material, rather than comprising a strip extending throughout the height of the bag, thus effecting a substantial saving in the amount of window-forming material required in manufacture.

The apparatus generally comprises means for supplying to a bag machine a continuous web of bag material having a series of window openings therein spaced at equal intervals corresponding to the length of bags to be made in the bag machine, together with a patch feeder for feeding patches of window-forming material, such as cellophane, into position over the window openings in the web at a fixed point in the path of travel of the web, the patches being fed in the direction of travel of the web and at substantially the same speed as the speed of the web, and a patch former for intermittently forming patches from a continuous strip of window-forming material and delivering the patches to the patch feeder for application to the web. The patches may be adhesively secured to the web by providing means for applying adhesive to the web around the window openings therein. The web also may have the window openings cut therein in the course of its travel to the bag machine by a cutter operating in properly timed relation to the speed of the web, the patch feeder and the patch former. The apparatus is particularly constructed to form and apply patches of cellophane and incorporates special features for operation upon this material, which is otherwise difficult to work. Other features will be in part apparent and in part pointed out hereinafter.

The invention accordingly comprises the constructions and methods hereinafter described, the scope of the invention being indicated in the following claims.

In the accompanying drawings, in which one of various possible embodiments of the invention is illustrated:

2

Fig. 1 is an elevation of one side of an apparatus embodying the invention, a bag machine being illustrated generally diagrammatically;

Fig. 2 is a plan view of the apparatus;

5 Fig. 3 is an elevation of the other side of the apparatus, partly in section on line 3—3 of Fig. 2;

Fig. 4 is an enlarged vertical section taken on line 4—4 of Fig. 2, illustrating per se a cutting unit of the apparatus;

10 Fig. 5 is an enlarged vertical section taken on line 5—5 of Fig. 4;

Fig. 6 is an enlarged vertical section taken on line 6—6 of Fig. 4;

15 Fig. 7 is a horizontal section taken substantially on line 7—7 of Fig. 1;

Fig. 8 is an enlarged plan view of a coating unit of the apparatus per se, an intaglio roll of this unit being broken away;

Fig. 9 is a side elevation of Fig. 8;

20 Fig. 10 is an enlarged plan view of a cellophane unit of the apparatus per se;

Fig. 11 is a vertical section taken on line 11—11 of Fig. 10;

25 Fig. 12 is an enlarged plan view of certain drive mechanism;

Fig. 13 is a vertical section taken on line 13—13 of Fig. 12;

Fig. 14 is a plan view of a completed composite web formed by the apparatus of the invention;

30 Fig. 15 is a plan view of a window bag made from the web of Fig. 14; and

Fig. 16 is an enlarged section taken on line 16—16 of Fig. 15.

Similar reference characters indicate corresponding parts throughout the several views of 35 the drawings.

This invention is particularly concerned with the manufacture of two-ply paper bags having a window of flexible transparent sheet material, such as cellophane, in the front wall of the bag.

40 Such a bag is illustrated at 1 in Fig. 15 and is shown in Figs. 15 and 16 to comprise an outer printed ply 3 and an inner unprinted ply or liner 5 of kraft paper or the like. In the outer ply 3 in the front wall of the bag is a window opening 7.

45 In the inner ply or liner 5, in register with aperture 7, is a larger window opening 9. At 11 is shown a window of flexible transparent sheet material such as cellophane which closes the openings 7 and 9 while permitting the contents of 50 the bag to be seen. The window consists of a

rectangular patch of the transparent sheet material sandwiched between the plies in position closing the openings and adhered to the outer ply by adhesive 13 and to the inner ply by adhesive 15. As illustrated, the patch extends lengthwise of the bag. Its width is sufficiently greater than the diameter of the larger opening 9 to allow for application of adhesive 15 (and 13) but considerably less than the width of the front bag wall. Its length is greater than the diameter of the opening 9, but less than the length or height of the bag.

The bags 1 are automatically made in a continuous process by a conventional bag machine B (Fig. 1) from a special two-ply web W (Fig. 14) consisting of a printed paper web 17 having a series of the window openings 7 therein spaced at equal intervals along its length, and a liner web 19 having a series of the window openings 9 therein registering with the openings 7, with patches 11 sandwiched between the plies in position closing the openings and adhered to the printed paper ply 17 by adhesive 13 and to the liner ply 19 by adhesive 15. This invention is particularly concerned with the manufacture of the web W, which, in the bag machine, is formed into a tube, the latter being formed into individual bag tubes and then into bags 1. The printed web 17 forms the outer ply of the tube and hence forms the outer ply 3 of the bags; the liner web 19 forms the inner ply of the tube and hence forms the inner ply of the bags. The openings 7 (as well as the openings 9) are spaced apart longitudinally of the web a distance corresponding to the length of the individual bag tubes from which the bags are made. The bag machine B may be of any suitable conventional type for forming a continuously travelling multi-ply web of bag material into a tube and forming the tube into bags in a continuous process. Such machines are well known in the art.

Apparatus of this invention for forming the web W is shown generally to comprise a web-forming unit 21 mounted at the entrance end of the bag machine B. This unit includes a cutter unit 23 having means for cutting the window openings 9 in the liner web 19, a coating unit 25 having means for applying an adhesive such as paste in a pattern around the openings, and a cellophane unit 27 having means for forming the patches 11 from a continuous strip of cellophane and delivering the patches into position over the window openings 9 where they become adhered to the liner web 19. The web 19 with the patches 11 adhered thereto travels into the bag machine, where it is combined with the printed web 17 to form the composite web W, and the latter travels on through the bag machine where it is tubed and then formed into bags.

The liner web 19 is supplied from a web supply roll L mounted at the rearward end of the unit 21. It is guided for travel from the supply roll through the unit 21 to the bag machine in a predetermined path by various web guiding means to be described, being pulled from the supply roll by web feeding elements in the bag machine B at a predetermined speed dependent upon the speed at which the bags are formed. In the course of its travel through the unit 21, the liner web 19 is first operated upon by the cutter unit 23 which cuts the window openings 9 therein at properly spaced intervals. Then it travels through the coating unit 25 which applies paste to one of its sides in the pattern 15 around each of the window openings. Then it travels over a

combining guide roll 29 where the patches 11 are intermittently delivered by the cellophane unit 27 into position covering the window openings and become adhered to the web by the adhesive 15. Then it proceeds into the bag machine.

More particularly, the unit 21 is shown to comprise main vertical side frames 31 and 33, the frame 31 being on the left as viewed in the direction of travel of the liner web 19, and the frame 33 being on the right. These frames extend parallel to one another longitudinally of the unit and are transversely spaced apart a distance greater than the width of the widest web the apparatus is to accommodate. At the rearward ends of the frames are brackets 35 and 37 for supporting an arbor 39 carrying the liner web roll L. The cutter unit 23 (Figs. 1-6) extends transversely across the apparatus from frame to frame forward of the roll L, being supported at its ends on the tops of the frames. It comprises left and right side frames 41 and 43 tied together by an upper pair of channel bars 45 and a lower pair of channel bars 47. The upper bars 45 are spaced apart longitudinally of the apparatus i. e., in the direction of travel of the web, and support a pair of transversely spaced bearing guide members 51. These are spaced equal distances on opposite sides of the longitudinal center line of the cutter unit. They have vertical bearing guideways 53. Bearings 55 are vertically slidable in these guideways. A cutter roll 57 is journaled in the bearings. Fixed on this roll is a cutting die 59 having a cutting edge 61 of such geometrical contour as to cut the openings 9 in the liner web 19 in cooperation with an anvil roll 63. The bearings 55 are vertically adjustable to adjust the elevation of the cutter roll 57 by means of vertical adjusting screws 65. These screws are threaded at their lower ends into the bearings and extend upward through sleeves 67 adjustably threaded into the tops of the bearing guide members 51. The screws have portions 69 threaded in the sleeves. At their upper ends the screws have handwheels 71 for turning them.

The lower bars 47 are located under the upper bars 45 and support a pair of transversely spaced lower bearing guide members 73 under the upper bearing guide members 51. The bearing guide members 73 have vertical bearing guideways 75. Bearings 77 are vertically slidable in these guideways. The anvil roll 63 is journaled in these bearings. It comprises a hardened roll having axially spaced pins 79 projecting from its periphery for piercing the pieces of liner web material cut from the liner web 19 by the cutting die 59.

The bearings 77 are vertically adjustable to adjust the elevation of the anvil roll 63 by means of vertical adjusting screws 81. These screws are threaded at their upper ends into the bearings 77 and extend downward through holes in the bottoms of the bearing guide members 73. Collars 83 are pinned to the screws above the bottoms of the members 73 and bear against the bottoms of the members 73 to hold up the screws and the bearings 77. At their lower ends below the members 73 the screws have handwheels 85 for turning them.

The cutter roll 57 and the anvil roll 63 are positively driven through a cutter drive mechanism generally designated 87 in Fig. 4. As shown, this drive mechanism includes an upper shaft 89 and a lower shaft 91 journaled in bearings in the right side cutter frame 43 and in bearings in an outboard bearing bracket 93 carried by the frame 43. A gear 95 on the upper shaft 89 meshes with

a gear 97 on the lower shaft so that these shafts may be rotated in opposite directions. On the upper shaft 89 is a drive sprocket 99, driven by means to be described. The shaft 89 is coupled to the cutter roll 57 by shafting including universal joints 101 and a shaft 103. The shaft 91 is coupled to the anvil roll 63 by shafting including universal joints 105 and a shaft 107. The universal joints allow for adjustment in elevation of the cutter and anvil rolls.

The liner web 19 is led off the bottom of the web roll L and travels horizontally between the cutter roll 57 and the anvil roll 63, being guided for such travel by idler guide rolls 109 and 111 mounted on the main side frames 31 and 33 rearward and forward of the cutter unit 23. The cutter and anvil rolls are adjusted in elevation so that, as they rotate, upon every revolution of the rolls the cutting edge 61 of the cutting die 59 cuts through the web against the anvil roll to cut out a piece of web material and thus form the window openings 9 in the web. The anvil roll is so phased with respect to the cutter roll that the pins 79 pierce the cut-out piece of web material and carry it around with the anvil roll. The cutter roll is driven clockwise and the anvil roll counterclockwise as viewed from the left side of the cutter. The pins 79 are raked in the direction of rotation of the anvil roll. When the cutting die 59 cuts out the pieces of web material the pins extend through the pieces into a depression 113 in the die bounded by the cutting edge 61 of the die.

The cutter unit also includes means for stripping the waste paper pieces from the pins 79. This means comprises a stripper blade 115 having a beveled stripping edge 117 positioned to enter between a piece of waste paper and the anvil roll to strip the paper from the pins. The blade 115 has notches 119 in its stripping edge 117 providing passageway for the pins 79 projecting from the anvil roll. The blade is mounted for transverse adjustment on a slotted transverse bar 121 carried by slotted arms 123 which are fixed to but vertically adjustable on the inner sides of the lower bearing guide members 73. Thus, the blade 115 is vertically and transversely adjustable properly to position its beveled edge 117 for stripping the pieces of waste paper from the pins 79 and properly to position the notches 119 in respect to the pins.

From the idler roll 111, the web 19, now having the window openings 9 therein, travels downward and around an idler guide roll 131, thence generally horizontally under the coating unit 25, and thence upward around a pair of idler guide rolls 133 and 135 and through the coating unit. The latter, illustrated in detail in Figs. 7, 8 and 9, comprises an intaglio coating roll 137 for applying an annular pattern of paste around each of the window openings 9 in the liner web 19. The intaglio roll has two diametrically opposed raised peripheral surface areas 139 which lie in a cylindrical surface. These areas 139, being raised, are disposed radially outward of the remaining surface areas 141 of the roll between the raised areas. In each of the raised surface areas 139 is an annular groove 143 of such outline as to apply an annular pattern of paste around each of the window openings 9 in the liner web 19. The diameter of the intaglio roll across the raised areas 139 is such that the paste pattern is applied around two successive window openings upon each revolution of the roll.

Paste is applied to the intaglio roll by a paste

roll 145 rotating in a paste pot 147. The paste roll 145 is positioned to transfer paste to the raised areas 139 of the intaglio roll, particularly into the paste grooves 143 in these areas. A doctor blade 149 is located to scrape paste from the paste roll 145 to control the amount of paste applied to the intaglio roll. Another doctor blade 151 is located to scrape against the raised areas of the intaglio roll ahead of the line of engagement of the intaglio roll and the liner web 19 to clean all the paste off the raised areas of the intaglio roll except that retained in the paste-receiving grooves 143. The liner web 19 is pressed against the intaglio roll for transfer of paste from the grooves 143 to the web by means of a soft surfaced idler presser roll 153, for example, a rubber roll.

In greater detail, the coating unit 25 comprises vertical side plates 155 having outwardly extending bottom flanges 157 which rest upon frame members 159. At the forward ends of the side plates are upwardly extending members 161. The intaglio roll 137 is fixed on a shaft 163 journaled in bearings 165 at the upper ends of members 161. The side plates are adjustably fixed to the frame members 159 by bolts 167 extending through longitudinal slots 169 in the flanges 157. They are adapted to be moved longitudinally of the apparatus to adjust the position of the intaglio roll by means of adjusting screws 171. These screws extend longitudinally of the apparatus, being held against axial movement but being rotary in angle brackets 173 fixed to the frame members 159, and being threaded through blocks 175 fixed to the rearward edges of the side plates 155.

The paste roll 145 is fixed on a shaft 177 journaled in bearing blocks 179. These slide on tracks 181 and are adjustably fixed to the side plates 155 by bolts 183 extending through longitudinal slots 185 in the side plates. They are adapted to be moved longitudinally of the apparatus to adjust the position of the paste roll 145 relative to the intaglio roll 137 by means of adjusting screws 187 which are rotary in the blocks 175 but fixed against axial movement therein. The doctor blade 149 is carried by a shaft 189 journaled in the bearing blocks 179. Fixed on this shaft adjacent the left bearing block 179 is a lever 191. An adjusting screw 193 is threaded through the lever with its lower end bearing against a block 195 fixed to the left bearing block 179. Another screw 197 is threaded in the block 195 and extends through a notch 199 at the end of the lever. The screw 197 has a shoulder 201 bearing downward against the end of the lever to keep the lever from moving upward. The screw 193 keeps the lever from moving downward. The doctor blade 151 is carried by a shaft 203 journaled in bearings at the forward ends of the side plates 155. On the left end of this shaft is a lever 205. A spring 207 attached to the lever biases the doctor blade toward the intaglio roll 137. Movement of the doctor blade toward the roll 137 is limited by a screw 209 threaded through the lever and bearing against a block 211 fixed to the left side plate 155. The presser roll 153 is carried by a pair of arms 213 extending from a transverse bar 215 fixed at its ends in the main side frames 31 and 33, as indicated at 217.

The cellophane unit 27, illustrated in Figs. 1, 2, 10 and 11, comprises left and right vertical side plates 223 and 225. These extend longitudinally of the apparatus and are transversely spaced a

distance greater than the width of the cellophane strip to be separated into patches. At the rearward ends of the side plates 223 and 225 are upwardly extending brackets 227 having bearings 229 at their upper ends for journaling an arbor 231 carrying a supply roll C of cellophane strip 235. The latter is pulled from the supply roll and fed forward through the cellophane unit by upper and lower feed rolls 239 and 241. The lower roll 241 is fixed on a shaft 242 journalled in bearings 243 fixed in the lower ends of slots 245 extending down from the upper edge of the vertical side plates 223 and 225. The upper roll 239 is fixed on a shaft 246 journalled in bearings 247 which are vertically slideable in the slots. The bearings 247 are held in the slots by screws 249 adjustably threaded in cap plates 251. The latter are resiliently held against the upper edges of the side plates by compression springs 253 reacting from nuts 255 on studs 257 threaded into the upper edges of the side plates through openings in the cap plates 251. The feed rolls 239 and 241 are driven at such speed as to feed the cellophane strip at a speed lower than that of the liner web 19, as will be made clear.

The cellophane strip issuing from between the feed rolls 239 and 241 travels through a first cutting unit 259 adapted to make two aligned spaced transverse cuts in the strip without completely severing it. The unit 259 comprises a lower anvil roll 263 fixed on a shaft 264 journalled in bearings 265 fixed in the lower ends of slots 267 which extend down from the upper edges of the vertical side plates 223 and 225. Cooperating with the anvil roll to cut the cellophane strip is a rotary cutter member comprising a blade holder 269 fixed on a shaft 271 journalled in bearings 273 which are vertically slideable in the slots 267. Studs 275 extend upward from the bearings 273 slidably through sleeves 277 threaded in head members 279 on the upper edges of the side plates 223 and 225 and also through apertures in bridge members 280 located above the head members 279. Nuts 281 are threaded on the upper ends of the studs to adjust the elevation of the bearings 273. The bearings are biased downward by compression springs 283 surrounding the studs and located between the head members 279 and the bearings. The blade holder 269 comprises a roll having a transverse groove 285 receiving a blade 287. The latter has two individual cutting edges 289 spaced along its length and is fixed in the groove by suitable fasteners 291 with the cutting edges protruding from the periphery of the blade holder roll 269. As illustrated, each of the cutting edges 289 is about one-fifth as long as the width of the cellophane strip. The centers of the edges 289 are spaced on opposite sides of the longitudinal center line of the cellophane strip about one-fifth the width of the cellophane strip.

The cellophane strip issuing from the cutting mechanism 259 is guided and fed forward by a strip feeding mechanism, generally designated 293, comprising a pair of upper endless feed belts 295 and a pair of lower endless feed belts 297. The strip is guided and fed forward by and between opposed horizontal reaches 299 and 301 of the upper and lower belts. The lower belts 297 are trained around rearward and forward pulleys 303 and 305, respectively, and around tensioning pulleys 307. The rear pulleys 303 for the lower belts are fixed on a shaft 309 journalled in bearings 311 fixed in the lower ends of slots 313 in the side plates 223 and 225. The forward pulleys 305 for the lower belts are loose on a shaft 315

journalled in bearings 317 fixed in the lower ends of slots 319 in the side plates 223 and 225. The tension pulleys 307 for the lower belts are carried by a shaft 321 mounted at its ends in arms 323 which extend radially from a transverse bar 325 spanning the side plates. The arms are clamped to the bar in such angular position as properly to tension the lower belts. The pulleys for the lower belts are so located as to guide the two lower belts for travel in transversely spaced vertical planes, centered in respect to the spaced cutting edges 289 of the cutting mechanism 259, as illustrated in Fig. 10.

The upper belts 295 are trained around rearward and forward pulleys 333 and 335, respectively, and around tensioning pulleys 337. The rear pulleys 333 for the upper belts are fixed on a shaft 339 journalled in bearings 341 vertically slideable in the slots 313. The bearings 341 are biased upward by springs 343 compressed between the lower bearings 311 and the bearings 341, and are held downward by screws 345 threaded in the head members 279. The forward pulleys 335 for the upper belts are loose on a shaft 347 journalled in bearings 349 vertically slideable in the slots 319. The bearings 349 are biased upward by springs 351 and held downward by screws 353 threaded in the head members 279. The tension pulleys 337 for the upper belts are carried by a shaft 355 mounted at its ends in arms 357 which extend radially from a transverse bar 359 spanning the side plates 223 and 225. The arms are clamped to the bar in such angular position as properly to tension the upper belts. The pulleys for the upper belts are located to guide the upper belts for travel in the same vertical planes as the lower belts.

Located between the rearward pulleys 303 and 333 and the forward pulleys 305 and 335 is a second strip cutting unit, generally designated 363, adapted to complete the cutting of the strip across the line of severance initiated by the cuts made by the cutting edges 289. The unit 363 comprises a lower anvil roll 365 fixed on a shaft 366 journalled in bearings 367 fixed in the lower ends of slots 369 which extend down from the upper edges of the vertical side plates 223 and 225. The anvil roll is peripherally grooved to receive the horizontal reaches 301 of the lower belts 297. Cooperating with the anvil roll to cut the cellophane strip is a rotary cutter member comprising a blade holder 373 fixed on a shaft 375 journalled in bearings 377 which are vertically slideable in the slots 369. Studs 379 extend upward from the bearings 377 slidably through sleeves 381 threaded in the head members 279 and through apertures in the bridge members 280. Nuts 383 are threaded on the upper ends of the studs to adjust the elevation of the bearings 377. The bearings are biased downward by compression springs 385 surrounding the studs and located between the head members 279 and the bearings. The blade holder 373 comprises a roll having a transverse groove 387 receiving a blade 389 and having annular peripheral grooves 391 receiving the horizontal reaches 299 of the upper belts 295. The blade 389 has three individual cutting edges 393 spaced along its length protruding from the blade holder roll 373 to cut the cellophane strip between the cuts previously made by the cutting edges 289 and transversely outward from the latter cuts to the edges of the cellophane strip, thereby to sever the strip completely across its width. The blade 389 is fixed in the groove by suitable fasteners 395.

The horizontal reaches 299 of the upper belts are received in the two notches between the three cutting edges 393.

The forward end of the cellophane strip leaving the strip feeding mechanism 293 enters a patch feeder, generally designated 401, which is adapted to feed patches at a speed substantially equal to the speed of travel of the liner web 19, this speed being higher than the speed at which the strip is fed forward by the draw rolls 239 and 241 and by the strip feeding mechanism 293. The patch feeder 401 comprises an upper endless feed belt 403 and a lower endless feed belt 405. The strip is fed forward by and between opposed horizontal reaches 407 and 409 of the upper and lower belts. The lower belt 405 is trained around rearward and forward pulleys 411 and 413, and around a tensioning pulley 415. The rearward pulley 411 for the lower belt 405 is fixed on the shaft 315 between the pulleys 305. The forward pulley 413 for the lower belt is carried by a shaft 417 mounted at its ends in the cellophane unit side plates 223 and 225. The side plates have forward extensions 419 located above the level of the lower horizontal reach of the upper belt 403, and extending forward from the forward pulley 413 for the lower belt 405. The tension pulley 415 for the lower belt 405 is carried by a shaft 421 mounted at its ends in arms 423 which extend radially from the bar 325. The arms are clamped to the bar in such angular relation as properly to tension the belt 405.

The upper belt 403 is trained around rearward and forward pulleys 427 and 429, and around a tensioning pulley 431. The rearward pulley 427 is fixed on the shaft 347 between the pulleys 335. The forward pulley 429 is carried by a shaft 433 mounted at its ends adjacent the forward ends of the side plate extensions 419. The tension pulley 431 is mounted at the end of an arm 435 which extends radially from the bar 359. The arm is clamped to the bar in such angular position as properly to tension the belt. The horizontal reach 407 of the upper belt 403 is pressed toward the horizontal reach 409 of the lower belt 405 by a presser roll 439 carried by a lever 441 pivoted on a bracket 443 attached to the side plate 223. The roll 439 is biased down against the horizontal reach of the upper belt by a spring 445 connected between the bracket and the lever.

Rearwardly adjacent the pulley 429 is a roll 437 carried by a transverse shaft 449 mounted at its ends in the side plate extensions 419. This roll has an annular peripheral groove 451 deeper than the thickness of the belt 403. The belt 403 travels within this groove. The cellophane unit 27 is mounted on a platform 453 supported in such longitudinal position that the portion of the horizontal reach of the upper belt 403 forward of the pulley 413 engages the liner web 19 travelling over the combining roll 29, and in such transverse position that the cellophane strip is longitudinally aligned with the cutting die 59 and the paste grooves 143. The roll 447 engages the liner web 19 somewhat forward of the combining roll. The latter is journaled at its ends in the main side frames 31 and 33. The cellophane unit is equipped with horizontal table plates 457 on opposite sides of the horizontal reach of the lower belt 405 for supporting the patch being fed forward by the belts 403 and 405.

Patches 11 delivered by the patch feeder 401 of the cellophane unit are combined with the liner web 19 at the combining guide roll 29 in

a manner that will be made clear. The liner web 19 with the patches 11 adhered thereto travels from the combining roll into the bag machine B. The latter generally includes frames 459 having elevated roll-holding brackets 461 at their rearward ends for supporting an arbor 463 carrying a supply roll P of the printed web 17. Web 17 has previously had window openings 7 cut therein prior to being wound up into the supply roll P. The printed web 17 is pulled from the supply roll P through a coating unit 467 in the bag machine which applies paste 13 in a pattern around the window openings 7. Coating unit 467 is a conventional part of the conventional bag machine. The printed web 17, coated with paste, meets the liner web 19 (having the patches 11 adhered thereto) at a combining roll 469 where the printed web becomes adhered to the patches 11 by the adhesive 13 to form the composite web W. The web W leaving the combining roll 469 then travels through a coating unit 471 which applies the paste for the bag tube seam and then on through the bag machine where it is formed into a tube, the tube being segmented into individual bag lengths, and each bag length being formed with a bottom.

As illustrated, the apparatus of this invention is driven from the bag machine B through a power take-off shaft 473 (Figs. 2, 3 and 7) to correlate the speed of the cutter unit 23, the coating unit 25 and the cellophane unit 27 with the speed of travel of the liner web 19 as determined by the bag machine. The power take-off shaft 473 drives a countershaft 475 through bevel gearing 477. The countershaft 475 extends transversely of the apparatus under the cellophane unit 27 and above the coating unit 25, being journaled in a bearing 479 on the right main side frame 33, and in a bearing 481 carried by a longitudinal frame member 482. The countershaft 475 is coupled to drive a main drive shaft 483 for the apparatus through a compensating differential 485. The main drive shaft 483 is journaled in a bearing 487 in the main side frame 33 and in a bearing 489 carried by the longitudinal frame member 482. As shown, the differential 485 comprises an epicyclic bevel gear train having a bevel gear 491 journaled on the shaft 483 for rotation relative to the shaft, a bevel gear 493 fixed on the shaft and idler bevel pinions 495 rotary with respect to the shaft in mesh with the bevel gears. The bevel gear 491 is part of a cluster having a spur gear 493 in mesh with a similar spur gear 496 on the countershaft 475. The bevel pinions 495 are carried by the hub of a worm wheel 497 in mesh with a worm 499 on a vertical adjusting rod 501. The latter is mounted for rotation in bearings carried by the frame and has an adjusting knob 505 at its upper end. The worm maintains the worm wheel 497 and pinions 495 stationary with respect to the shaft 483, but may be turned by means of the rod 501 to turn the worm wheel 497 and to rotate the pinions 495 around the shaft 483. Thus, drive shaft 483 is always driven at the same speed relative to the power take-off shaft 473 (and the bag machine), but its phase in relation to the power take-off shaft 473 (and the bag machine) may be adjusted by turning the knob 505, even while the apparatus is being driven.

The cutter unit 23 is driven from the main drive shaft 483 by a chain 507 trained around a sprocket 509 fixed on the drive shaft and the

sprocket 99 on the shaft 89 of the cutter unit. The coating unit 25 is driven from the main drive shaft 483 by a chain drive including a sprocket 511 on the shaft 483, sprockets 513 and 515 on the intaglio roll shaft 163 and the paste roll shaft 177, respectively, and a chain 517 trained around these sprockets to drive the intaglio roll and the paste roll in the same direction.

The cellophane unit 27 is driven from the main drive shaft 483 through a transverse shaft 519 journaled in bearings 521 mounted on the platform 453 to the right of the cellophane unit. The shaft 519 is driven from the main drive shaft 483 through a chain and sprocket drive including a sprocket 523 on the shaft 483, a sprocket 525 on the shaft 519, and a chain 527 extending through an opening 528 in the platform. The shaft 519 is coupled as indicated at 529 to a cellophane unit main drive shaft 531 journaled in bearings on the cellophane unit side plates 223 and 225.

Adjustably fixed on the left end of the main cellophane unit drive shaft 531 outward of the left side plate 223 is a gear 535. This meshes with a gear 537 on the left end of the anvil roll shaft 264 to drive the anvil roll 263. Gear 537 also meshes with a gear 539 on the blade holder shaft 271 to drive the blade holder 269 and the cutting blade 287. Fixed on the right end of the anvil roll shaft 264 outward of the right side plate 225 is a sprocket 541. A chain 553 is trained around this sprocket and around a sprocket 545 on the right end of the lower feed roll shaft 242 to drive the lower feed roll 241. A gear 547 on the left end of the shaft 242 meshes with a gear 549 on the left end of the upper feed roll shaft 246 to drive the upper feed roll 239. A sprocket 551 is fixed on the right end of the lower feed roll shaft 242 inward of the sprocket 545. A chain 553 is trained around the sprocket 551 and a sprocket 555 on the right end of the shaft 309 to drive the rear pulleys 303 for the lower belts 297. Fixed on the shaft 309 within and adjacent the right side plate 225 is a gear 557. This meshes with a gear 559 on the shaft 339 to drive the rear pulleys 333 for the upper belts 295. An idler gear 561 is mounted for rotation at 563 on the outside of the left side plate 223 in mesh with the gear 537. The idler gear meshes with a gear 565 adjustably fixed on the left end of the shaft 366 to drive the anvil roll 365. Fixed on the right end of the shaft 366 is a gear 567 which meshes with a gear 569 on the right end of the blade holder shaft 375 to drive the blade holder 373 and the blade 389. The shaft 366 is provided at its left end with a knob 571 for manually turning the shaft to turn the blade 389 to its properly phased position in respect to the blade 287.

The forward belts 403 and 405 are driven from the cellophane unit main drive shaft 531 through a drive including a conventional speed changer 573 having an infinitely variable speed ratio. The shaft 531 is coupled to drive the input shaft 575 of the speed changer by a chain and sprocket drive 577. The output shaft 579 of the speed changer is coupled directly to the shaft 347 to which the rearward pulley 421 for the upper belt 403 is fixed to drive the upper belt. A gear 581 on the shaft 347 meshes with a gear 583 on the shaft 315 to drive the lower belt 405 at the same speed as the upper belt. The speed of the belts 403 and 405 may be adjusted to match the speed of travel of the liner web 19 by adjusting the 75 the cutting unit 23, the cutting die 69, in coopera-

speed changer 573, the latter having an adjusting knob 585 for this purpose.

The liner web 19 is guided for travel through the coating unit 25 by the idler roll 135 and an idler roll 587. From the latter roll it travels over the combining roll and on into the bag machine B. The speed of the belts 403 and 405 of the patch feeder 401 is adjusted to match or at least substantially to match the speed of the liner web 19 by adjusting the speed changer 573. The drive for the web cutter unit 23 is so designed as to drive the cutter roll 57 at an angular speed such that the linear speed of the cutting edge 61 of the die 59 matches or at least substantially matches the linear speed of the liner web 19. The drive for the coating unit 25 is so designed that the raised peripheral areas 139 of the intaglio roll 137 travel at a linear speed which matches or at least substantially matches the speed of the liner web 19. The drive for the cutting units 259 and 363 (including chain 527, shafts 519 and 531, gear 535 meshing with gear 537, gear 537 meshing with gear 539 and also with idler gear 561, the latter meshing with gear 565, and gear 567 meshing with gear 569) is so designed and phased that the cutting units make one revolution for each bag-forming operation of the bag machine and thus cut a patch for every bag. The cutting units 259 and 363 are so phased in respect to the speed of the cellophane strip that the blade 389 of the cutting unit 363 cuts the strip in the same line as the cuts made by the blade 287 of the cutting unit 259. The hub of the gear 535 is adjustably fixed on the shaft 531 so that the entire cellophane unit may be adjusted to be in phase with the bag machine. The hub of the gear 565 is adjustably fixed on the shaft 366 so that the cutting units 259 and 363 may be adjusted to be in phase with each other. The drive from the shaft 264 to the feed rolls 239 and 241 is so designed as to feed the cellophane strip at a speed such that patches of the desired length (shorter than the distance between successive window openings in the web 19) are cut from the strip. This speed is less than the speed of the patch-feeding belts 403 and 405 and less than the speed of the web 19. The drive for the strip-feeding belts 295 and 297 through chain 543 is so designed as to drive the belts at a linear speed slightly greater than the speed at which the strip is fed by the rolls 239 and 241. This maintains the portion of the strip between the cutting units 259 and 363 under tension.

Operation is as follows:

The supply roll L of the liner web 19 is journaled by means of the arbor 39 in offset relation to the longitudinal center line of the apparatus so that the window openings 9 are cut in properly offset position, i. e., on one side of the center line of the web, as illustrated in Fig. 2. The supply roll P of the printed web 17 is mounted slightly offset from the supply roll L of liner web 19 to provide for the usual transverse offset 8 of these webs (see Fig. 14). It will be understood that the window openings 7 are pre-cut in the printed web 17 to align with the window openings 9 cut in the liner web 19 with the webs combined in such offset relation.

The liner web 19 is pulled through the web-forming unit 21 from the supply roll L by the bag machine B at a predetermined speed and in the path predetermined by the idler guide rolls 109, 111, 121, 133, 135, 587 and the combining roll 29. In the course of the travel of the web 19 through 75 the cutting unit 23, the cutting die 69, in coopera-

tion with the anvil roll 63, cuts out pieces of the web to form the window openings 9 therein. These openings are formed at equally spaced intervals along the length of the web, the spacing of the openings being equal to the length of the bag tubes from which the bags 1 are formed. The cut-out pieces of web are impaled on the pins 79 and carried around with the anvil roll 63 to the stripper blade 115, which strips them from the pins.

The liner web 19, leaving the cutter unit 23 with the window openings 9 cut therein, is guided for travel through the coating unit 25. In the course of travel of the web through the coating unit, the intaglio roll 137 applies paste from the grooves 143 to the side of the web engaging the roll in a pattern around each window opening 9 in the web. This transfer of paste from the grooves 143 to the web takes place at a fixed point in the path of travel of the web. The intaglio roll rotates in such phase relation to the web that the paste grooves 143 meet the window openings in the web. The two paste grooves 143 are circumferentially spaced a distance corresponding to the spacing of the window openings. From the coating unit 25, the web 19 travels over the combining roll 29, with its paste-bearing side facing upward and engaged by the forward portion of the horizontal reach of the upper patch-feeding belt 403, and then on into the bag machine B.

As the web 19 travels through the web-forming unit 21 at the speed determined by the speed of the bag machine B, the cellophane unit 27 is driven in timed relation to the speed of the web. The feed rolls 239 and 241 pull the cellophane strip 235 from the supply roll C at a speed lower than the speed of the web 19. The belts 295 and 297 cooperate with the feed rolls 239 and 241 as a strip feeder for feeding the strip through the two cutting units 259 and 363 under tension at this speed. As the cutting edges 289 on the roll 269 meet the anvil roll 263 they cut through the cellophane strip across a portion of its width without completely severing the strip, thus initiating a transverse line of severance. This line of severance travels forward and as the cutting edges 393 on the roll 373 meet the anvil roll 365, they cut through the strip across the remainder of its width, this cutting off a length of the strip at its foremost end to form a patch 11. The length of the patch is determined by the length of strip that travels through the cutters during one revolution thereof. A patch 11 is thus formed for each window opening 9 in the liner web 19.

The end of the cellophane strip leaving the feed belts 295 and 297 is guided between the patch-feeding belts 403 and 405. As soon as the second cutting unit 363 completes the severance of the strip to form a patch 11, the belts 403 and 405 feed the patch forward away from the freshly cut end of the cellophane strip in the direction of travel of the web 19 and at the same or substantially the same speed as the speed of the web. Since the patch 11 is fed forward faster than the cellophane strip 235, the patch separates from the end of the slower-moving strip, as indicated at S in Fig. 10. This accounts for the spacing of the patches 11 on the liner web 19. The action of the cellophane strip cutters is timed to occur at intervals related to the passage of a window opening 9 over the combining roll 29 in such manner that patches 11 are fed into position over the window openings, becoming adhered to the liner web 19 by the adhesive 15

previously applied to the web by the coating unit 25. The patches travel out from between the belts 403 and 405 under the forward portion of the upper belt 403 and on to the liner web 19 travelling over the combining roll 29.

The liner web 19, with the patches 11 adhered thereto over the window openings 9, then travels into the bag machine B where the printed web 17 is combined therewith. It will be understood that the web 17 is phased for registry of the window openings 7 therein with the window openings 9 in the liner web 19.

The patch feeder 401 is located to feed the patches 11 over the window openings 9 in the web 19 at a fixed point in the path of travel of the web, viz., at the combining roll 29. The strip feeding rolls 239 and 241, the belts 295 and 297, and the cutting units 259 and 363 constitute a patch former for intermittently forming the patches 11 from the strip 235 of cellophane at its foremost end and for delivering the patches to the patch feeder 401 for application to the web 19. This patch former arrangement is particularly suitable for forming patches from the strip 235 of cellophane, which is a difficult material to work.

It will be understood that the liner web 19 could be pre-cut with the window openings 9 prior to being wound into the roll L, in which case the liner web cutting unit 23 could be omitted. It is preferred, however, to incorporate the window opening cutter in the apparatus for applying the patches to the liner web. It will be further understood that it is within the scope of the invention to affix the patches 11 to the liner web 19 other than by the adhesive 15 applied to the liner web.

In view of the above, it will be seen that the several objects of the invention are achieved and other advantageous results attained.

As many changes could be made in the above constructions, methods and materials without departing from the scope of the invention, it is intended that all matter contained in the above description or shown in the accompanying drawings shall be interpreted as illustrative and not in a limiting sense.

We claim:

1. In combination, means for guiding two continuous webs each having a series of window openings therein spaced at equal intervals along their length for travel at a predetermined speed in spaced-apart paths which ultimately meet at a combining guide for combining the two webs in superposed relation, with the window openings thereof in register, means for applying adhesive to the side of one of said webs which faces the other web in a pattern around each window opening in said one web, a strip feeder for continuously feeding a strip of window-forming material toward said one web at a speed lower than the speed of the web, a cutter for transversely severing the strip into patches shorter than the spacing of the window openings, and a patch feeder for speeding up and feeding the patches of window-forming material severed from the strip into position covering the window openings in said one web at a fixed point in the path of its travel past the point of application of the adhesive, the patch feeder being adapted to feed the patches on to the adhesive-bearing side of said one web in the direction of its travel and at substantially the same speed.
2. In combination, means for guiding a first continuous web having a series of window open-

ings therein spaced at equal intervals along its length for travel in a first predetermined path at a predetermined speed, means for applying adhesive to one side of said first web in a pattern around each window opening at a fixed point in the path of its travel, a strip feeder for continuously feeding a strip of window-forming material toward said first web at a speed lower than the speed of said web, a cutter for transversely severing the strip into patches shorter than the spacing of the window openings, a patch feeder for speeding up and feeding the patches of window-forming material severed from the strip into position over the window openings in said first web at a fixed point in the path of its travel past the point of application of the adhesive, the patch feeder being adapted to feed the patches on to the adhesive-bearing side of said first web in the direction of its travel and at substantially the same speed, and means for guiding a second continuous web having a series of window openings therein spaced at said equal intervals along its length for travel at said predetermined speed in a second predetermined path which ultimately meets said first predetermined path at a means for combining the two webs located past the point of application of the patches to the first web, said webs being combined with their window openings in register.

3. Apparatus for forming a continuous composite web consisting of two individual webs having registering window openings therein spaced at intervals along their length with patches of window-forming material sandwiched between the plies in position closing the window openings and adhered to the individual webs, comprising a support for a supply roll of one of said webs, a combining guide over which said one web may be pulled from the supply roll at a predetermined speed, a cutter for cutting the window openings in said one web as it is pulled from the supply roll, a coating unit for applying adhesive in a pattern around the window openings in said one web as it travels from said cutter to said combining guide, a strip feeder for continuously feeding a strip of window-forming material toward said one web at a speed lower than the speed of the web, a cutter for transversely severing the strip into patches shorter than the spacing of the window openings, a patch feeder located to receive the patches of window-forming material severed from the strip and to speed them up and feed them into position over the window openings in said one web as they travel over the combining guide, a support for a supply roll of the other of said webs, and a second combining guide over which both webs may be pulled and at which they may be combined after the patches have been applied to said one web with their window openings in register.

4. The method of making two-ply window bags comprising the steps of continuously feeding into a bag machine at bag machine speed a first web having a series of window openings therein spaced at equal intervals along the length of the web, applying adhesive in a pattern around the window openings in said first web as it travels toward the machine, continuously feeding a strip of window-forming material toward said first web at a speed lower than web speed, segmenting the strip into patches shorter than the spacing of the window openings in the web, speeding up the segmented patches to the speed of the web and feeding them on to the web over the window openings therein and upon the patterns of ad-

hesive surrounding the window openings, continuously feeding into the bag machine at bag machine speed a second web having a series of window openings spaced at said equal intervals along its length and combining it with the first web subsequent to the application of the patches to the first web with the window openings of the two webs in register, thus forming a composite two-ply windowed web, said composite two-ply windowed web, in the bag machine, being formed into a tube, and the tube being segmented into individual bag lengths and each bag length formed with a bottom.

5. The method set forth in claim 4 further comprising the step of applying adhesive in a pattern around the window openings in the second web prior to combining it with said first web.

6. In combination with a bag machine adapted automatically to form a web of bag material traveling at a predetermined speed into a tube, to segment the tube into individual bag lengths, and to bottom each bag length, apparatus for supplying two-ply window bag material to the machine comprising means for continuously feeding into the machine two continuous webs each having a series of window openings therein spaced at equal intervals along their length with the webs guided to travel at said predetermined speed in spaced-apart paths which ultimately meet at a combining guide for combining the two webs in superposed relation and with the window openings thereof in register, means for applying adhesive to the side of one of said webs which faces the other web in a pattern around each window opening in said one web, a strip feeder for continuously feeding a strip of window-forming material toward said one web at a speed lower than the speed of the web, a cutter for transversely severing the strip into patches shorter than the spacing of the window openings, and a patch feeder for speeding up and feeding the patches of window-forming material severed from the strip into position covering the window openings in said one web at a fixed point in the path of its travel past the point of application of the adhesive, the patch feeder being adapted to feed the patches on to the adhesive-bearing side of said one web in the direction of its travel and at substantially the same speed.

7. In combination with a bag machine adapted automatically to form a web of bag material traveling at a predetermined speed into a tube, to segment the tube into individual bag lengths, and to bottom each bag length, apparatus for supplying two-ply window bag material to the machine comprising a support for a supply roll of one of said plies, a combining guide over which said one ply is pulled from the supply roll at said predetermined speed, a cutter for cutting window openings in said one ply as it is pulled from the supply roll, a coating unit for applying adhesive in a pattern around the window openings in said one ply as it travels from said cutter to said combining guide, a strip feeder for continuously feeding a strip of window-forming material toward said one ply at a speed lower than the speed of the ply, a cutter for transversely severing the strip into patches shorter than the spacing of the window openings, a patch feeder located to receive the patches of window-forming material severed from the strip and to speed them up and feed them into position over the window openings in said one ply as they travel over the combining guide, a support for a supply roll of the other of said plies, said other ply having

17

window openings pre-cut therein, and a second combining guide over which both plies are pulled and at which they are combined with their window openings in register after the patches have been applied to said one ply.
